UNITED STATES PATENT OFFICE.

JOSEPH SCHNEIBLE, OF NEW YORK, N. Y.

REGULATING-VALVE.

SPECIFICATION forming part of Letters Patent No. 633,662, dated September 26, 1899.

Application filed July 24, 1899. Serial No. 724,892. (No model.)

To all whom it may concern:

Be it known that I, JOSEPH SCHNEIBLE, a citizen of the United States, residing in the borough of Manhattan, city of New York, State 5 of New York, have invented certain new and useful Improvements in Regulating-Valves, of which the following is a specification, reference being had to the accompanying drawing, forming a part hereof.

10 This invention relates to valves which depend for their operation upon the action of a diaphragm subject to the pressure of the fluid controlled by the valve and in which the spring, which in some cases acts upon the dia- 15 phragm in opposition to the pressure of the fluid, is dispensed with, the diaphragm itself being subject to fluid-pressure on both sides.

The objects of the invention are to produce a compact and simple valve without external 20 parts and to promote convenience and reduce cost in manufacture, while providing a reliable and sensitive valve.

The invention is illustrated for purposes of explanation in the accompanying drawing, 25 which represents a vertical central section of a valve which embodies the improvements.

The main valve A is of the balanced variety, having a double seat *aa*, with which coöperates a valve-plug B, formed in the usual manner, except as hereinafter indicated. The diaphragm shell or chamber C is supported directly upon the body A of the main valve, the neck A² between the body of the valve and the valve-chamber forming a guide in 35 which the valve plug or stem is free to move. The diaphragm D may be secured, as usual, between the two parts of the diaphragm shell or chamber and is connected to the valve plug or stem B, as by means of the heads or plates 40 G'. Both chambers on opposite sides of the diaphragm communicate with the discharge side of the main valve through the valve stem or plug B, which is bored axially, a restricted port or passage b' communicating with the 45 chamber above the diaphragm, while another port or passage b' communicates with the chamber below the diaphragm.

A regulating-diaphragm chamber E is suitably supported upon the main-diaphragm 50 chamber C, virtually forming, with the upper part thereof, one chamber, and communicates through a passage e with the supply side of

the main valve. The passage of the fluid into the chamber E is controlled by a valve-plug F, which is carried by the regulating-diaphragm G. The latter is suitably supported between the shell or chamber E and the spring-box H and is acted upon in opposition to the fluid-pressure within the shell or chamber E by a spring I, the pressure of the spring being 55 regulated by a hand-screw K and follower k in the usual manner. This diaphragm G may be much smaller than the diaphragm D and is easily removed and replaced whenever necessary. 60

The operation of the improved valve is as follows: It being assumed that the hand-screw K has been turned backward until the diaphragm G has been relieved from the pressure of the spring I, the tension of the dia- 70 phragm itself will cause the valve F to close the passage e. There being then no overpressure on the upper side of the diaphragm D, the tension of this diaphragm D, assisted, if necessary, by a spring B', will close the main 75 valve at *aa*. As soon as the screw K is turned to compress the spring I and depress the dia- phragm G the passage e will be opened by the movement of the valve-plug F. The fluid- 80 pressure thus created on the upper side of the diaphragm D will depress the same, opening the main valve at *aa*. Fluid-pressure will thus be created on the discharge side of the main valve, and through the port or pas- 85 sage b' pressure on the under side of the dia- phragm D is established, which is nearly equal to the pressure on the upper side of the same diaphragm. A sufficient overpres- 90 sure on the upper side of the diaphragm to cause the device to respond quickly to any variation in pressure is maintained by means of the restricted port or passage b between the chamber on the upper side of the dia- phragm and the discharge side of the main valve, which permits the fluid to escape from 95 such chamber less freely than it is admitted thereto.

It will be obvious that upon any decrease in pressure on the discharge side of the valve, and consequently on the under side of the dia- 100 phragm D, the valve-plug B will be lowered and the area of the valve-opening increased, while in case of any increase in pressure on the supply side of the valve the dia-

- phragm G will be raised and the passage e will be closed by the valve F, and the overpressure on the upper side of the diaphragm being quickly relieved through the port or passage b the diaphragm D will rise, reducing the area of the valve-opening at a a. In case of a decrease of pressure on the supply side of the main valve the pressure in the chamber E will be decreased to the same extent, 5
- 10 the diaphragm G will be depressed under the action of the spring, the opening of the valve F will be increased, the overpressure on the upper side of the diaphragm D will be increased, the diaphragm D will be correspondingly depressed, and the area of the valve-opening at a a increased. The pressure on the discharge side of the main valve is thus maintained substantially uniform at all times, 15 regardless of variations of pressure on the supply.
- 20 The subjection of both sides of the main diaphragm to nearly equal fluid-pressures prevents any buckling or straining of the diaphragm, and, moreover, the pressures on opposite sides are distributed equally over all 25 portions of the diaphragm, while in the case of a diaphragm supported by a spring the pressure on the spring side is applied only to an area equal to the effective area on the supporting-plate.
- 25 The action of the main or operating diaphragm is of course controlled or regulated by any suitable means, such as the supplemental-diaphragm spring and adjusting-screw shown; but even if a supplemental diaphragm is employed it will be seen that the operating-diaphragm is much larger and can be made much lighter than a spring-supported diaphragm of the same size.

When the improved valve is used for regulating steam, for which purpose it is specially designed, it will be observed that by reason of its compactness and the absence of external parts there is little opportunity for condensation of the steam, and, moreover, that there is no chance for interference with the 40 operation of the valve by accumulation of water of condensation.

I claim as my invention—

1. A regulating-valve comprising a valve plug and seat, a diaphragm to which said valve-plug is connected, chambers on opposite sides of said diaphragm, said valve-plug having formed therein a passage communicating with said chambers and with the discharge side of the valve, a passage to one of said chambers from the supply side of the valve, and means to control said passage.

2. A regulating-valve comprising a valve plug and seat, a diaphragm to which said valve-plug is connected, chambers on opposite sides of said diaphragm, said valve-plug having formed therein a passage communicating with said chambers and with the discharge side of the valve, a supplemental diaphragm and diaphragm-chamber communicating with one of the first-named chambers, a passage from the supply side of the valve to said supplemental-diaphragm chamber, and a valve connected to the supplemental diaphragm to control said passage.

This specification signed and witnessed this 17th day of July, A. D. 1899.

JOSEPH SCHNEIBLE.
